Primary Examiner — Catherine S Posthauer*Assistant Examiner* — Joan E. Diehl(74) *Attorney, Agent, or Firm* — Taylor Duma LLP**CLAIM**

The ornamental design for a packaging insert, as shown and described.

DESCRIPTION

FIG. 1 is a front, top, left perspective view of the claimed design.

FIG. 2 is a front view of the claimed design.

FIG. 3 is a rear view of the claimed design.

FIG. 4 is a left side view of the claimed design.

FIG. 5 is a right side view of the claimed design.

FIG. 6 is a top view of the claimed design.

FIG. 7 is a bottom view of the claimed design.

FIG. 8 is a front, top, left perspective view of the claimed design with a surrounding box in environment.

FIG. 9 is a front, top, left perspective view of the claimed design shown in use with an exemplary lid; and,

FIG. 10 is a top view thereof.

Evenly spaced broken lines shown represent parts of the article as well as environmental subject matter of an exemplary lid that form no part of the claimed design. Dot-dot-dash lines shown in FIG. 8 represent environmental subject matter of an exemplary box and form no part thereof.
